(57) **CLAIM**

The ornamental design for the tape measure case, as shown and described.

DESCRIPTION

FIG. 1 is a perspective view of a tape measure case in accordance with a first embodiment of my invention; FIG. 2 is a right side view of the tape measure case of FIG. 1;

FIG. 3 is a left side view of the tape measure case of FIG. 1;

FIG. 4 is a rear view of the tape measure case of FIG. 1; FIG. 5 is a front view of the tape measure case of FIG. 1; FIG. 6 is a top view of the tape measure case of FIG. 1; and, FIG. 7 is a bottom view of the tape measure case of FIG. 1. The broken lines of the tape measure case in FIGS. 1-7 are illustrative of portions of the tape measure case that form no part of the claimed design.
